(57) **CLAIM**

The ornamental design for a trash receptacle lid, as shown and described.

DESCRIPTION

FIG. 1 is a bottom perspective view of a trash receptacle lid.
FIG. 2 is a top plan view thereof.

FIG. 3 is a bottom plan view thereof.

FIG. 4 is a right-side view thereof.

FIG. 5 is a left-side view thereof.

FIG. 6 is a front elevational view thereof; and,

FIG. 7 is a rear elevational view thereof.

The broken lines in the figures show portions of the trash receptacle lid that form no part of the claimed design.

1 Claim, 5 Drawing Sheets
